Attorney's

UNITED STATES PATENT OFFICE.

HOWARD B. SHERMAN, OF BATTLE CREEK, MICHIGAN.

CONDUIT-HANGER.

1,245,047.

Specification of Letters Patent. Patented Oct. 30, 1917.

Application filed December 22, 1916. Serial No. 138,374.

To all whom it may concern:

Be it known that I, HOWARD B. SHERMAN, a citizen of the United States, residing at Battle Creek, in the county of Calhoun and 5 State of Michigan, have invented certain new and useful Improvements in Conduit-Hangers; and I hereby declare that the following is a full, clear, and exact description thereof, reference being had to the accompanying drawings, which form part of this 10 specification.

This invention is a novel improvement in hangers for pipes, conduits, electric cables, and like objects, which I will hereafter refer to under the general inclusive term "conduits." The objects of the invention are to provide a novel and very simple and easily applied means for suspending such conduits from I-beams and the like in a convenient, 15 safe and substantial manner to avoid cumbersome and complex constructions; and to provide hangers which can be applied by unskilled workmen, and by which the conduits can be suspended either parallel with 20 or at right angles to the I-beams or supports.

The invention provides novel clamp-members adapted to be engaged with the edges of the I-beam flange; tie-bolts rigidly connecting the clamp-members; and novel 25 means for suspending the conduit from such tie-bolt.

It is very important that the clamp-members should be stiff and rigid so that they will not bend or drop away from the flange 35 when the tie-bolt is tightened; and the tie-bolts must be sufficiently strong to bear the strain, and must approximate in length the width of the flanges, which vary greatly.

In the accompanying drawings I have 40 illustrated a practical embodiment of the invention and will explain same with reference thereto and summarize in the claims the essential features and combinations of parts for which protection is desired.

45 In said drawings—

Figure 1 is a view of the complete hanger attached to an I-beam; the hanger-ring being arranged so that the conduit will extend longitudinally of the beam.

50 Fig. 2 is a similar view showing how the hanger-ring can be arranged to suspend the conduit at right angles to the beam.

Fig. 3 is a perspective view of the preferred form of hanger-ring detached.

55 Fig. 4 is a perspective view of one of the clamp-members detached.

Fig. 5 is a view showing a form of hanger used for cast iron pipe or heavy objects.

Fig. 6 is a detail sectional view of part of Fig. 5.

The clamp-members may be formed in any desired manner as by casting or stamping out of suitable metal. Each clamp member preferably has an oblong base or outer portion 1^a surrounded and stiffened by an 60 inwardly projecting flange 1^b. In the sides of this flange near its top are notches 1^c adapted to engage the edges of the flange of an I-beam, I, or other suitable support, as shown in Figs. 1—2—5. The upper edges of 70 said notches rest upon the top of the flange and support the clamp-members thereon; and the lower edges of the notches underlie the flange of the I-beam as shown in Fig. 1. The portion 1^a of the clamp-member is perforated as at 1^e below the notches 1^c for the 75 passage of a tie-bolt 2. The clamp members, by reason of their peculiar formation, are very strong; can be readily cast; and will securely engage the flange.

80 Similar but opposite clamp-members are engaged with opposite edges of the flange of the beam, and the tie-bolt 2 extends through the openings 1^e in the clamp-members and is secured by means of a nut 2^e on its threaded end, exterior to one of the clamp-members as shown. By tightening this nut 2^e the clamp-members are securely engaged with the flange of the I-beam.

85 The portions 1^f of the flanges of the clamp-members underlie the flange of the I-beam and prevent the clamp-members from tilting thereon, and enable the tie-bolt to draw the clamp-members squarely and tightly against the edges of the I-beam and clamp 90 them securely thereagainst. Before the tie-bolt is engaged with both the clamp-members the hanger-ring, or conduit suspending device, is engaged therewith. As shown in 95 Figs. 1—3 the hanger-ring is formed of a 100 metal strip bent to approximately circular form and having an opening at one side where the ends of the strip are bent outwardly to form ears 3^a which are perforated for the passage of a bolt 4 which is provided 105 with a nut 4^a as usual in clamps.

Opposite the said opening the hanger-ring is formed with a radially projecting bend or loop 3^c which may be directly engaged with the bolt 2 as in Fig. 2, so as to 110 suspend the hanger-ring at right angles to the length of the bolt and parallel with the

length of the I-beam, and when the loop is thus engaged with the bolt the conduit C, suspended by the ring, would extend longitudinally of the bolt and at right angles 5 to the I-beam. The sides of the loop 3^e however are perforated as at 3^e for the passage of the tie-bolt, and may be engaged with the bolt 2 as indicated in Fig. 1; and when so engaged the hanger-ring will be 10 suspended from the tie-bolt in a plane parallel with the bolt and at right angles to the I-beam so that the conduit suspended thereby will extend at right angles to the bolt and longitudinally of the I-beam. This novel 15 perforated loop of the hanger-ring is of great practical utility as it enables the hanger-ring to be readily suspended directly from the bolt either at right angles thereto or parallel therewith, so that the 20 conduit can be arranged either longitudinally of the I-beam or transversely thereof.

Where very heavy conduits are to be suspended, or it is desired to suspend a conduit from beams arranged at different elevations, the devices shown in Figs. 5 and 6 25 may be used. In this instance in place of the hanger-ring 3 a ring 5 is used, said ring having perforated ears 5^a connected by means of a bolt 5^c to an eye 6^b on the lower 30 end of a casting 6 having a threaded socket 6^a screwed onto the lower threaded end of a rod 7 the upper threaded end of which rod is screwed into a threaded socket 8^a in a casting 8, having an eye 8^b through which 35 the tie-bolt 2 passes.

The ring 5 may be made of any desired 40 diameter to suit the size of the conduit to be suspended. The rod 7 can be made of suitable length to suspend the conduit any desired distance beneath the tie-bolt 2.

The clamp-members enable the bolt to be arranged close beneath the beam, and in the form shown in Figs. 1 and 2 the conduit can be suspended very closely beneath the beam. With the construction shown in Fig. 45 5 the conduit can be suspended any desired distance below the beam.

The hangers can be readily attached to flanges of various widths, by using tie-bolts 50 of suitable length. Hanger-rings can be provided of different sizes; and they also can be readily adjusted either parallel with or at right angles to the tie-bolts.

The hangers being very simple can be 55 readily attached to an I-beam or suitable support by ordinary unskilled workmen. When such a hanger is properly fastened to an I-beam, as shown in the drawings, it is stiff and rigid; will not bend or drop

from the flange; is not liable to loosen; will 60 remain securely in place and will substantially support the conduit in position either parallel with or at right angles to the beam.

What I claim is:

1. In a hanger, opposite clamp-members 65 each having a base portion and inwardly projecting flanges notched to engage the edge of a support, and said base being perforated below the notches for the passage of a tie bolt; in combination with a tie bolt 70 passing through the perforations in the clamp-members; and a hanger ring having a radially extending loop with perforations in its sides, substantially as described.

2. In a hanger, opposite clamp-members 75 each consisting of a base portion having projecting side flanges provided with notches adapted to engage the edge of a support, and said base having a perforation for the passage of a tie bolt below said notches; in 80 combination with a tie bolt passing through the perforations in the clamp-members to secure them to the support; and a hanger ring having a radially extending loop adapted 85 to engage the bolt to suspend the ring therefrom at right angles to the bolt, said loop having perforations in its sides whereby the ring can be suspended from the bolt in a plane parallel with the bolt.

3. A clamp-member for the purpose specified, having a base portion and an inwardly projecting flange surrounding this base portion, said flange being provided with notches in its opposite sides adapted to engage the edge of an I-beam to support the clamp-member thereon, and said base portion being perforated below said notches for the passage of a tie bolt, substantially as described. 95

4. A clamp-member for the purpose specified, consisting of a base portion and inwardly projecting flanges on the sides of said base portion, said flanges being provided with notches adapted to engage the edge of a support, and said base having a 100 perforation for the passage of a tie bolt below said notches when the member is in position for use, substantially as described.

5. A hanger-ring for the purpose specified having a radially projecting open loop 110 adapted to engage a bolt, the sides of this loop being perforated, whereby the ring can be suspended either by catching the loop over a member, or passing the member through said perforations in the loop. 115

In testimony that I claim the foregoing as my own, I affix my signature.

HOWARD B. SHERMAN.
